IRA H. WILLIAMS, OF MAPLE CREEK, SASKATCHEWAN, CANADA, ASSIGNOR OF ONE-HALF TO CLARENCE B. WILLIAMS, OF PENCE, SASKATCHEWAN, CANADA.

POWER MECHANISM.

1,164,690.

Specification of Letters Patent. Patented Dec. 21, 1915.

Application filed April 27, 1914, Serial No. 834,847. Renewed April 30, 1915. Serial No. 25,051.

To all whom it may concern:

Be it known that I, IRA H. WILLIAMS, a subject of the King of Great Britain, residing at Maple Creek, Province of Saskatchewan, Canada, have invented certain new and useful Improvements in Power Mechanism, of which the following is a specification.

This invention relates to power mechanism of the converting motion type, and the primary object of the invention is to organize a plurality of geared eccentric devices in such manner that the one will operate with respect to the other by a movable wedging action to lift or shift a lever or movable part in one direction and permit a return of the lever or movable part by gravitation of the eccentric devices in the opposite direction, and thereby increase the power effectiveness of a prime operating means which may be of any preferred form.

A further object of the invention is to utilize a plurality of geared eccentric devices, one of which at least is connected to a lever or movable device, as an actuating means for the lever or movable device and operated through the medium of a pulling action relatively to one of the eccentric devices under the control of an eccentric element operated by a prime power generating means to increase the effectiveness of the latter and also to convert rotary motion into reciprocating or oscillating motion.

With these and other objects and advantages in view the invention consists in the construction and arrangement of the several parts which will be hereinafter more fully explained in one form to demonstrate the practicability of the improved mechanical organization.

In the drawing: Figure 1 is a side elevation of mechanism embodying the features of the invention and showing the same operatively applied to a reciprocating or oscillating lever. Fig. 2 is a top plan view of the mechanism shown by Fig. 1. Figs. 3 and 4 are detail plan views of parts of the mechanism including the lever actuated by the improved devices. Fig. 5 is a side elevation of the mechanism embodying a modification in structure in a portion thereof. Fig. 6 is a top plan view of the mechanism shown by Fig. 5.

The numeral 5 designates a prime power generating means including a shaft 6 and a belt wheel or pulley 7 held by suitable

bearing uprights, supports or pillars 8. This power generating means may be that disclosed by the application of Clarence B. Williams and Ira H. Williams, filed May 28, 1913, Serial Number 770,555, or any other suitable power generating means. A shaft 9 is mounted in suitable bearing uprights 10 at a distance from the uprights or pillars 8, and thereon is secured a band wheel or pulley 11 in alinement with a larger band wheel 12 on the power shaft 6, the pulleys 11 and 12 being engaged by or having a band or belt 13 trained thereover for transmitting the power from shaft 6 to shaft 7. As shown by Figs. 1 and 2, a crescent-shaped or other analogous eccentric 14 is mounted on the shaft 9 and embodies a convex wiping edge 15 and a concave edge 16 forming the wall of a recess 17 opposed to the edge 15. On the base, which may be provided by a suitable structure or consist of the ground surface, as at 17^a, constituting the support for the mechanism, a bar 18 is horizontally disposed, said bar 18 being of the form shown by Fig. 4 and having one end bifurcated, as at 19. This bar 18 is held in fixed position and at the end opposite the bifurcation thereof a yoke or looped support 20 is secured and rises a suitable distance above the said bar to receive the fulcrum 21 of an oscillating or vertically reciprocating power lever 22 which may be of any suitable length and constructed as shown by Fig. 3 with a longitudinal slot 23. The lever 22 may engage or be attached to a pump rod 24 or any other mechanical device that is adapted to be operated by the movement of the said lever 22. In the bifurcation 19 of the bar 18 a spur gear 25 is eccentrically mounted by means of a bolt or pin 26 extending therethrough and the opposite portions of the bar 18, as shown by Fig. 1. The gear 25 may be adjusted to vary its eccentricity by forming the same with a plurality of openings 27, and by shifting the gear into different positions the stroke and rapidity of movement of the same may be readily changed. In the slot 23 of the power lever 22 a gear 28 is eccentrically mounted by means of a bolt or pin 29 passing through the opposite side portions of the lever and the said gear 28, and the latter is also adjustable to vary its throw and rapidity of movement by forming the same with a plurality of openings 30 which may be engaged

by the pin or bolt 29 in accordance with the adjustment of the gear 25. The gears 25 and 28 are precisely alike in diameter and are similarly toothed, said gears always being held in mesh, and when the gears are in normal position the portion of the gear 25 at the greatest peripheral distance from the fulcrum or pin or bolt 26 engages the portion of the gear 28 peripherally nearest to the fulcrum pin or bolt 29 therefor, as clearly shown by Fig. 1. The gear 28 has an arm 31 secured thereto at an angle and projecting to a point under the shaft 9 and carries a friction wheel or rotatable element 32 which is peripherally engaged by the edge 15 of the eccentric 14.

The operation of the device as thus far described is very simple and is as follows: The shaft 9 is rotated by the power shaft 6 through the medium of the pulley 7, belt 13 and pulley 11 so as to cause the eccentric 14 to rotate in the direction of the arrow shown thereon. The wheel, roller or rotatable element 32 being always held in engagement with the edge of the eccentric 14 and normally engaging the latter edge at the point nearest the portion secured to the shaft 9 or penetrated by the latter, the said wheel or rotatable element 32 will be pressed downwardly as the eccentric 14 rotates and the downward depression of the wheel or rotatable element 32 will correspondingly move the arm 31 in the same direction and pull or rotate the gear 28 toward the shaft 9 and eccentric 14, and this movement of the arm 31 and gear 28 will continue until the high end of the eccentric passes the upper central portion of the wheel or rotatable element 32, when the latter will move into the recess 17 and permit the arm 31 to rise, the elevation of the said arm and the wheel or rotatable element 32 being accomplished through the gravitating movement of the gear 28 and its companion gear 25. As the gear 28 is pulled over eccentrically on its fulcrum 29 it will rotate the gear 25 and cause the latter to turn equally on its fulcrum or the pin or bolt 26 and gradually bring the portions of the peripheries of the two gears 28 and 25 increasing in distance from the eccentric fulcrums of the said gears together and institute a wedging action which will operate to force the power lever 22 upwardly and correspondingly move the mechanical part that may be actuated thereby, as for instance the pump rod 24. This movement of the gears 28 and 25 will continue until the wheel or rotatable element 32 has passed into the recess 17 of the eccentric 14, and the gears 28 and 25 are so mounted and held in normal position relatively to each other that when the arm 31 and the wheel or rotatable element 32 are released from downward depression or permitted to rise by coming into engagement with the

wall 16 of the recess 17, the said gears 28 and 25 will automatically return to normal position for the reason that they are not caused to overthrow their fulcrum points. The downward depression of the arm 31 and the wheel or rotatable element 32 and the consequent operation of the gears 28 and 25 to elevate the power lever 22 and the successive release and automatic depression of the said power lever owing to the weight of the gears 28 and 25 will be rapidly effected and will regularly ensue, and hence the power lever 22 will have a regular oscillation imparted thereto with increased power effectiveness relatively to the prime power generating means, by reason of the eccentricity of the two gears 28 and 25 which always remain in mesh. The power lever 22, as above noted, may be very advantageously used in connection with a pump rod or piston, or it may be a part of a pressure device or any other mechanism to which it is desired to apply or attach the said lever.

The structure shown by Figs. 5 and 6 is in all essentials similar to that disclosed by Figs. 1 and 2, and similar reference characters are applied to corresponding parts. In the organization as shown by Figs. 5 and 6, however, the arm 31 has its outer end bifurcated, as at 33, and therein a gear 34 is eccentrically mounted through the medium of a bolt or pin 35, and instead of the eccentric 14, as shown by Figs. 1 and 2, a gear 36 of the same dimensions as the gear 34 is eccentrically mounted on the shaft 9, the gears 34 and 36 being always retained in mesh similarly to the gears 28 and 25. Primarily or when the gears 34 and 36 are in normal position, the fulcrum pin or bolt 35 of the gear 34 is in vertical alignment with and close to the shaft 9 directly under the latter, and as the gear 36 is rotated the portions of the two gears 34 and 36 increasing gradually in peripheral distance, especially from the pin or bolt 35 and the shaft 9, will move together regularly and the increasing distance as above referred to will effect a depression of the arm 31 and the gear 34 until the maximum peripheral distances of the gears 34 and 36 relatively to the pin or bolt 35 and shaft 9 are reached, when the said arm 31 and gear 34 will be permitted to rise and the gears 28 and 25 will return to normal position as shown, and at such time the power lever 22 will have been moved upwardly its maximum distance and then depressed to the position shown by Fig. 5. The wedging action of the gears 28 and 25 in eccentric relation as hereinbefore explained will be in all respects similar to that of like gears in the construction shown by Figs. 1 and 2, and as the arm 31 never passes the eccentric fulcrum point of the gear 28, the two gears 28 and 25 will gravitate or automatically swing around to nor-

mal position on the return or rise movement of the arm 31 and the gear 34.

The improved power mechanism above explained may be applied to various mechanisms as stated, and it will be noted that not only is the prime power generating means effectively used with increased power, due to the eccentricity of the gears 28 and 25, but that rotary motion is simultaneously converted into oscillating or reciprocating motion through the actuation of the power lever 22. It is proposed to modify the dimensions and general proportions of the parts of the improved mechanism to adapt 15 the same to various uses.

What is claimed is:

1. In a power mechanism of the class specified, prime power generating means, eccentric devices in operative contact with each other, one of said eccentric devices having a depressible arm fixed thereto, a reciprocating device to which the said eccentric device having the arm is connected, and means for actuating the eccentric devices 20 from the power generating means to set up a wedging action of the eccentric devices to operate said reciprocating device.

2. In a power mechanism of the class specified, prime power generating means, a reciprocating device, eccentric gear devices, one of said eccentric devices having a depressible arm fixed thereto and also connected to the reciprocating device, and eccentrically mounted means for operating the eccentric gear devices through engagement with said arm from the prime power generating means.

3. In a power mechanism of the class specified, prime power generating means, a reciprocating device, eccentric devices in relative and operative adjacency, one eccentric device having a depressible arm fixed thereto and carrying a roller and also connected to the reciprocating device, and an eccentric operatively connected to said prime power generating means for operating one eccentric device to actuate the other similar device and effect a movement of the reciprocating device.

4. In a power mechanism of the class specified, prime power generating means, a reciprocating member, eccentric gear devices continually in mesh, one of the gear devices being connected to said member and also having a depressible arm fixed thereto, and means for operating the gear device connected to the member to effect a wedging

action relatively to the other gear device to effect movement of the member in one direction, the gear devices having an automatic 60 return movement in the opposite direction when the maximum eccentric engagement of the gear devices is reached.

5. In a power mechanism of the class specified, a support, a reciprocating member, a gear device eccentrically connected thereto and also provided with a depressible arm fixed thereto to effect rotation thereof, a counteracting eccentrically mounted gear device held by said support adjacent to and 65 engaging that connected to the member, eccentric means for actuating the gear device connected to the member, and prime power generating means for operating the eccentric means.

6. In a power mechanism of the class specified, a support, a reciprocating member, a gear device eccentrically connected thereto and having a depressible arm fixed thereto, a counteracting eccentrically mounted gear device held by said support adjacent to and engaging that connected to the member, eccentrically mounted means for engaging and actuating the free end of the arm of the one gear device and provided 80 with a clearance recess in one side for the portion of the arm engaged thereby, and prime power generating means for operating the eccentric means.

7. In a power mechanism of the class 90 specified, a support, a reciprocating member, a gear device eccentrically connected thereto and having a fixed arm with a free end carrying a roller, a counteracting eccentrically mounted gear device held by the support, an eccentrically mounted means co-operating with the movable engaging element to depress the arm and rotate the gear device secured thereto, the said eccentrically mounted means having a clearance space 100 in one side for the roller to permit the gear devices to automatically move back to normal position after they have reached maximum extent of their movement, and prime power generating mechanism for operating 105 the said eccentrically mounted means.

In testimony whereof I have hereunto set my hand in presence of two subscribing witnesses.

IRA H. WILLIAMS.
